UNITED STATES PATENT OFFICE.

JOHN A. RUTHERFORD, OF RICHMOND, VIRGINIA.

CENTER-SLOT STEEL FURNITURE.

1,342,030.

Specification of Letters Patent. Patented June 1, 1920.

Application filed May 9, 1919. Serial No. 295,964.

To all whom it may concern:

Be it known that I, JOHN A. RUTHERFORD, a citizen of the United States, residing at Richmond, in the county of Henrico and State of Virginia, have invented certain new and useful Improvements in Center-Slot Steel Furniture, of which the following is a specification.

The invention relates to printers' furniture and has for its object to provide metal furniture which is labor saving and insures a perfect and solid square lock-up of printers' form in any size whatever, either large or small and which will obviate any springing or bending and insure absolute register of press forms which is essential for the make up of various multi-colored register work. Moreover, the present invention provides metal furniture which will guard against the possibility of the type matter, quads, leads, slugs, and other material from working up in any kind of form to be used in printing.

In accordance with the present invention the steel furniture is provided with a center slot and end mortises and may be made up in any desired lengths in multiples of half inches so that the parts may be rapidly and accurately assembled, the center slot always falling in the center of any half inch combination to be made up. As a result the work of the printer in making up and locking a form is greatly facilitated with the assurance that the several forms will register when printing in more than one color.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

In the accompanying drawing, Figure 1 is a top view of a form made up of different lengths of center slot and end mortises, steel furniture embodying the invention; and

Fig. 2 is a perspective view of a single length of such furniture.

Fig. 1 represents a printing form or lock-up embodying steel furniture having center

slot and end mortises, the same being arranged within a chase 1 of ordinary construction and made secure therein by quoins 55 2 in a manner well understood. The forms are comprised between ordinary furniture 3 which is disposed between the members of the chase and the outer lengths of the center slot steel furniture. 60

The numeral 4 designates lengths of steel furniture embodying the invention, each of such lengths being provided with a center slot 5 and end mortises 6. The furniture 4 which is preferably of steel may be made in any desired lengths preferably in multiples of half inches so that they may be assembled rapidly and accurately, the center slot 5 always falling in the center of any half inch combination to be made up. The end mortises correspond in depth to the depth of the center slot 5, thereby admitting of corresponding lengths fitting accurately. When the furniture is arranged with two or more lengths in line it is disposed with the mortise ends abutting, as indicated most clearly in Fig. 1. The space formed by the mortises at the ends of adjacent sections is adapted to receive the projecting ends of sections disposed side by side with their slots facing outwardly in opposite directions, as shown most clearly in Fig. 1. The lengths of the furniture being uniform or in multiple insures forms of uniform dimensions so that the matter set up will register and insure 85 neat and accurate work in multi-color printing. It will be understood that furniture for printers' use constructed in accordance with the invention enables a form to be made up with a minimum number of pieces 90 and when the form is made up the quoins may be arranged in line with the furniture separating the forms, thereby preventing any possible bending or distorting of the furniture which usually tends to throw the 95 forms out of line and which is the source of considerable trouble in work requiring the forms to register.

The foregoing description and the drawing have reference to what may be considered the preferred, or approved form of my invention. It is to be understood that I may make such changes in construction and arrangement and combination of parts, mate-

rials, dimensions, et cetera, as may prove expedient and fall within the scope of the appended claim.

Having thus fully described my invention, what I claim as new and desire to secure by Letters Patent is:—

Printers' furniture comprising lengths of steel, each length having a center slot and end mortises of uniform depth adapted to

form a corner thereby providing a rectangular frame, said mortises fitting the said center slots. 10

In testimony whereof I affix my signature in presence of two witnesses.

JOHN A. RUTHERFORD.
